TIRE TOOL OR THE LIKE

George A. Johnson, Saugus, Calif., assignor to Rojen B

Filed Sept. 23, 1974, Ser. No. 508,444

Term of patent 14 years

Int. Cl. D8—05

U.S. Cl. D8—31

Fig. 1

Fig. 3

Fig. 2

Fig. 5

Fig. 4

Fig. 6

Fig. 7

Fig. 8

FIG. 1 is a plan view of a first example of a tire tool or the like embodying the claimed design;

FIG. 2 is a frontal end view thereof;

FIG. 3 is a side elevational view thereof;

FIG. 4 is a side elevational view of a second example thereof;

FIG. 5 is a cross sectional view thereof, taken along the reference lines 5—5 of FIG. 4, showing configuration and contouring detail thereof; and

FIG. 6 is a plan view of a third example of a tire tool or the like embodying the claimed design;

FIG. 7 is a side elevational view of a fourth example thereof; and

FIG. 8 is a cross sectional view thereof taken along the reference lines 8—8 of FIG. 7.

All portions of the design are indicated contour lines in the figures to be substantially circularly cylindrical except where end views or cross sectional views indicate a

flattening or other shaping, the right hand, handle portion of the design as viewed in the figures and the entire body of the example shown in FIG. 6 being thus essentially right circular cylindrical.

I claim:

The ornamental design for a tire tool or the like, substantially as shown and described.
